APPARATUS FOR REPRODUCING THREE-DIMENSIONAL PATTERNS AND THE LIKE

Darnley E. Howard, Washington, D. C.

Application June 13, 1941, Serial No. 397,984

7 Claims. (Cl. 90—13.1)

The invention relates to apparatus for reproducing patterns and other articles and objects, and is particularly useful in reproducing three-dimensional objects. It is applicable to use in die sinking and in the reproduction of structures such as reliefs and intaglios, as well as industrial dies, molds, and other articles. It is an important aim of the invention to enable the reproduction of a sample of special form, specimens, sculptures, etc., without requiring high skill on the part of the operator as a machinist or tool maker. A further important object of the invention is to enable the ready reproduction of a given pattern, sample or model to scale, either larger or smaller than the original, without requiring mathematical computations or expert ability or training on the part of the operator.

A further aim is to enable the reproduction of an extremely intricate and peculiarly contoured object with great exactitude by the exercise of care in the manipulation of the apparatus, and with great rapidity.

Another important aim of the invention is to enable the use of originals which may be readily made by modeling manually or otherwise in soft materials if desired, including moist clay, as well as patterns made of harder materials, so that expensive metal casts or machined originals in hard materials are not essential, and the production of finished work may be effected from models or patterns made by persons unskilled in the operation of machinery or in pattern making, casting, etc.

A further important aim of the invention is to enable the production of a contour in any given plane of an original piece in a novel way. A still further important object is to make it possible for the operator to guide a tool in conformity with such contours without requiring any rigid or solid guide to contact the surface of the pattern.

Yet another important aim of this invention is to present a novel coordination of a work-engaging tool and an optical system operative in connection with a pattern contour for the reproduction of a solid having the same contour, whether in the same size, or larger or smaller in a definite scale relation, with great exactitude.

It is also an object to present novel apparatus and operative means for effecting the necessary relative movements of a pattern and tool-controlling means and of the tool and the work in scaled relation, adapted to actual size reproduction and to large or small scale reproductions.

Additional objects, advantages and features of invention reside in the construction, arrangement, and combination of parts involved in the embodiment of the invention, as will be understood from the following description and accompanying drawings, wherein

Figure 1 is an elevational view of a system embodying the necessary apparatus for carrying out my invention as to method and mechanism,

Figure 2 is a top view thereof;

Figure 3 is a cross sectional view of the pattern table on the line 3—3 of Figure 1, looking toward the right;

Figure 4 is an enlarged vertical section through the optical system, at right angles to the plane of Figure 3;

Figure 5 is a diagram of the system for controlling electrically the valves by which the fluid level is established on the pattern table;

Figure 6 is a detail elevational view of the objective lens mounting;

Figure 7 is a detail of the diaphragm or slide for forming the image of the tool, or, in other words the diameter and shape of a light beam to be projected beside the pattern piece.

Referring more particularly to the drawings, there is illustrated a pattern table 10, supported rotatively upon a non-rotating screw 11, mounted upon a suitable footing 12, which may be secured upon a floor 13 in any usual way. Over this footing and supported thereby, there is a worm sleeve or nut 14 in which the screw 11 is threaded, the nut having a ring gear 15 fixed thereon driven by means of a worm 16, mounted in a suitable bracket 17 secured upon the side of the foot piece 12. The table 10 is rotatable independently upon the screw 11 by means of a worm 18 mounted upon a bracket 19, fixed on the screw 11, and meshed with a gear 20 fixed on the under side of the table.

The table 10 is formed with a basin 21 in which a liquid 22 is maintained at a variable level independently of the level of the table and the basin, this liquid preferable being opaque and of a distinctive color contrasting with the color of the pattern to be reproduced, preferable white or gray. White is used where the pattern may be painted black or is of a very dark material, but a gray may be found preferable where the pattern is white.

Set upon the table 10 within the basin 21, there is a pattern 23 to be reproduced, a formal representation of a relief image of a human face being indicated in the present instance although various other forms of patterns may be used.

Means is provided for supplying the liquid 22, which in the present instance consists of a reservoir 24 at a higher level than the highest level to which the liquid is to be raised in the basin with suitable duct connection 25, leading through the table 10 and discharging within the basin, the flow of liquid through this duct being controlled by an electrically operated normally closed valve 26 arranged to open on closing of the circuit thereto. Also connected to the same duct at its low part there is a discharge duct 27, having a control valve 28 therein similar to the one 26 except that the effluent outlet of the valve has a discharge or drain pipe 29, which leads downward to a receiver 30 at a convenient point, or may discharge elsewhere, as preferred.

For operating the valves 26 and 28, a float 31 is mounted pivotally upon a suitable fixed support 32 of any suitable kind, the float operating a rigid arm 33 fixed with respect to the float and movable at its extremity between two sets of switches each including a movable contact operable by the arm 33 on movement of the latter in respective directions. One of these switch devices 34, is engaged in circuit with the valve 26, while the other switch, 35, is connected in the circuit with the valve 28. These switches are spring loaded and normally open, being closed by movement of the lever in respective directions from a medial position. Thus, in case of the raising of the table 10 as will be subsequently described, the float 31 will be caused to operate the switch 35 by action of the arm 33 thereon, causing a decanting of liquid from the basin 21, so that the liquid is restored to its original relation to the switch, at which time the switch 35 will be opened by return of the float and arm 33 to its initial or neutral position clearing both switch devices. On the other hand, when the table 10 is lowered, the lowering of the float 31 will close the switch 34, causing opening of the valve 26 by which an accretion of liquid in the bowl is effected from the supply in the reservoir 24, raising the level of the liquid 22 to that at which it stood in relation to the float mounting before the lowering of the table. The return of the float to its neutral position will open the switch and permit closing of the valve again, which will occur automatically.

An objective lens 36 is mounted on a fixed vertical axis coincident with the axis of the rotation of the table 10 by means of an arm 37, fixed on a work table base frame 55 to be described, and a bracket 37' mounted on an elevatable arm 67 adjustable on said frame, as will be described. The lens mounting in the present instance includes an outer barrel portion 38, fixed upon a telescopic extension 39 of the arm 37, and held in adjusted positions by a set screw 40. Within the barrel there is a lens-carrying sleeve 41 vertically slideable in the barrel, and held adjustably on its vertical axis by an adjusting device 42 of any desired kind, which may include in the present instance the separate support bracket 37' and lower rigid bracket arm 43 attached to the arm 67 of the work table device, which also serves to support the float mounting 32. A light beam source 44 is provided above the lens barrel, this being fixed upon a bracket 45, which is secured rigidly upon a sliding work table base 46 presently to be described, and movable in a fixed line toward and away from the table 10. The light beam source 44 in the present instance may include any approved electric lamp 47, condensers 48 and a photographic image slide 49 removably engaged in the lower part of the lamp mounting.

A rotary work table 50 is provided, mounted revolvably on the work table base 46 before referred to, the table being mounted for movement with the base 46 horizontally and being elevatable with the arm 67 by means of a screw 51 operable by a worm 52 mounted on a bracket 53 secured upon the foot 54 of the work table frame 55 having an upper arm 56 of fixed position carrying a milling head 57, the spindle of which carries the die sinking cutter or the like 58. Means is provided for rotating the table 50, consisting of a gear 59 with which a worm 60 is meshed, mounted upon a bracket 61 fixed on the work table base 46. The worm 60 is driven by a shaft 62 coupled to the shaft of a motor 63 fixed on the table base 46, and the worm 60 is also connected by a flexible shaft 64 to the worm 18 by which the pattern table 10 is rotated. The pitches of the worm and sizes of the gears 59 and 20 are so proportioned as to rotate the two tables in synchronism, so that the pattern will be always oriented on a horizontal axis extending in the same direction as the corresponding axis of the work.

The work table base 46 has a usual dovetail spline 65 engaged slidably in a carriage 66 mounted slidably upon a lower arm 67 in a direction at right angles to the direction of movement of the base 46 on the carriage. The arm 67 is vertically adjustable upon the frame as at 68, by means of the screw 52 and its operating means before described. The table base 46 may be moved upon the carriage by means of a hand screw 69 or any other approved means, and the carriage 66 is movable by means of a hand screw 70, both shown in Figure 1. The worm 52 by which the table 50 is raised and lowered is operated by means of a hand crank 71, and this worm and the worm 16 are connected by a flexible shaft 72, so that operation of the crank 71 will turn both screws simultaneously. The pitches of the worms and number of teeth on the gears by which the screws 11 and 51 are turned are such that the ratio of elevating movement of the tables 10 and 50 will be the same as the ratio or scale of size of the reproduction desired. The difference in the length of the incident beam 73 of light from the slide image 74 to the lens and the length of the projected portion of the beam at 75 from the lens to the surface of the liquid 22 is also in the same proportion: so that if the work is to be produced one-fifth the size of the original, the distance between the slide and lens is one fifth the distance from the lens to the liquid 22, and the table 50 is elevated one fifth as much as the table 10 on a given movement of the crank 71.

A piece of work 76 is indicated as being fixed on the table 50, in position to be engaged by the tool 58.

In the practice of my invention, the pattern 23 being suitably set in place on the table 10, and a piece of material 76 for the work being fixed on the table 50 in the same relation to the axis of rotation of the table 50 as the pattern is to the axis of rotation of the table 10, the screw 69 is operated to draw the table and base 46 to one limit of movement, or so as to clear the tool from the work. The work being reduced to a height nearly or quite corresponding to the height of the finished work, the apparatus is positioned and adjusted so that the liquid 22 is at a maximum level in the basin 21 with respect to the pattern when the float is in neutral position and both valves closed, this level being approximately at the apex or highest point of the pattern 23. The crank 71 is then operated to raise the table 10 and the table

50 so that the level of liquid and the pattern are raised a distance, and the work also elevated one fifth the distance. This causes the liquid level to overtake the float which was elevated the same distance as the work, and causes raising of the float and operation of the valve 28 until lowering of the liquid returns the float to neutral position where the valve again closes and establishes a liquid level in the basin fixed for the time being. This exposes a part of the pattern and discloses the contour of the base of the exposed part by its junction with the liquid 22. The tool 58 is now at a level to engage the work when the latter is moved into engagement with the tool. The screw 69 is now operated to move the work toward the tool, but the operator observes the location of the spot of light on the surface of the liquid caused by the incidence of the beam 15 thereon. By the proper proportioning of the image 74, the diameter of the light spot will correspond to an image of the cross section of the tool 58 enlarged in the same proportion which the pattern bears to the work to be produced. The operator now moves the base 46 inward while the motor 63 is in constant operation, so that all portions of material on the work are removed until the edge of the beam approaches or contacts the contour line at the junction of the liquid and pattern. Moving the base 46 also moves the bracket 45 and light source, so that the beam 15 swings in a direction opposite that in which the work is moved, and over a distance five times as great in the assumed ratio or scale of reproduction above indicated. The work is moved so as to swing the spot or image into recessed parts of the contour, and draws the work backward when the convexities of the contour are approaching the beam under rotation of the table 10, the corresponding rotation of the table 50, results in the tool 58 cutting the work 16 in corresponding form. After one or more turns of the tables so as to remove all material on the work beyond the finished contour at a given level attained by operation of the crank 71, the screw 69 is operated to draw the work away from the tool 58 again, while the crank 71 is again operated to raise the tables 10 and 50 to new levels. This brings the work to where it may again engage the tool outwardly of the contour to be produced, and causes the liquid to again function with the float and valves so that its level is lowered further around the pattern as before described, producing a new contour to be reproduced on the work in the manner already described. These steps are repeated until the complete reproduction of the pattern is effected, when the liquid level will be close to or at the base of the pattern.

After operation with a large diameter tool and corresponding slide 49, where there are contours involved having indentations too narrow for the spot or image to enter, another tool of smaller diameter and a new slide with correspondingly smaller image 74 are introduced, and the tooling of the work repeated as before beginning at such upper parts as require the smaller tool work. A final treatment with a pointed tool may be carried out.

In this way original works of high value and delicate finish may be reproduced without liability of injury, as well as more rugged pieces duplicated, or reproduced to scale.

Paper drawings of desired contours may be utilized by mounting them at the levels corresponding to the liquid levels referred to, or the table 10 may be disconnected from the elevating

drive 72 and the table 50 only elevated in the necessary successive degrees as respective contours on a drawing laid on the table 10 are followed; producing a three dimensional work from flat drawings.

When it is desired to change the scale of reproduction, the height of the arm 37 and light source are correspondingly adjusted and in reproducing from patterns the ratio of the drives at 16 and 52 changed similarly.

It will be understood that the liquid 22 may include an oil or the like to reduce surface tension, and may also include aqueous solutions or mixtures adapted to the uses contemplated. Also if desired in certain work the screw 61 and crank 71 may be coupled for simultaneous operation in conventional ways.

While I have disclosed my invention in the best forms which I have thus far constructed, it will be understood that this is purely exemplary, and that further improvements may be found obvious, including variations in the proportions of parts, substitution of materials, and mechanical equivalents, arrangement and construction of parts, all without departing from the spirit of the invention, as more particularly set forth and indicated by the appended claims.

I claim:

1. In a machine of the character described, a pattern table, means to establish a body of liquid thereon, means to vary the level of the liquid, a pointer device over the table movable universally, a work table, a tool mounted thereover, means to move the tool and work table relatively in a given direction, means to move said pointer and operative connections between the means to move the work table and tool relatively and said means to move the pointer, means to move the work table and tool relatively in a vertical direction, and operative connections between the last named means and said means to establish a liquid level, and means to rotate said tables in synchrony on a vertical axis.

2. In a tool of the character set forth in claim 1, a pointer device consisting of a light source, means to form a beam of predetermined cross section at the surface of the liquid, and means operatively associated with the means to move the work table horizontally to cause the beam to move in a direction corresponding to the movement of the work table.

3. Means for establishing a contour around a pattern consisting of a table support, means to establish a body of liquid around a pattern on the support, means to vary the level of said liquid at will, the means for varying the level of the liquid consisting of a liquid supply, a basin on the support, duct connections between said supply and the basin, a feed valve therein, a drain duct from said basin, a drain valve therein, a float adapted to float on the liquid in the basin and having a mounting independent of the table support and basin, means to move the float mounting and table support vertically relatively at will, and operative connections between said float and said valves, for alternative operation on respective opposite vertical relative movements.

4. Means for establishing a contour around a pattern consisting of a table support, means to establish a body of liquid around a pattern on the support, means to vary the level of said liquid at will, the means for varying the level of liquid consisting of a liquid supply, a basin on the support, a duct connection between said sup-

ply and the basin, a feed valve therein, a drain duct from said basin, a drain valve therein, a float adapted to float on the liquid in the basin and having a mounting independent of the table support and basin, means to move the float mounting and table support vertically relatively at will, operative connections between said float and said valves, for alternative operation on respective opposite vertical relative movements, said valves being normally closed, electrical means to open them, an arm movable by said float under variation of liquid level relatively, respective electrical circuits for said valves each including a circuit closer operatively associated with said arm and operable thereby alternately on movement of the arm in respective directions.

5. Means for establishing a contour around a pattern consisting of a table support, means to establish a body of liquid around a pattern on the support, means to vary the level of said liquid at will, the means for varying the level of liquid consisting of a liquid supply, a basin on the support, duct connections between said supply and the basin, a feed valve therein, a drain duct from said basin, a drain valve therein, a float adapted to float on the liquid in the basin and having a mounting independent of the table support and basin, means to move the float mounting and table support vertically relatively at will, and operative connections between said float and said valves, for alternative operation on respective opposite vertical relative movements, a work table, a tool thereover, means to move the table and tool relatively and operative connections between the last named means and said mounting of the float.

6. Means for establishing a contour around a pattern consisting of a table support, means to establish a body of liquid around a pattern on the support, means to vary the level of said liquid at will, the means for varying the liquid level consisting of a liquid supply, a basin on the support, duct connections between said supply and the basin, a feed valve therein, a drain duct from said basin, a drain valve therein, a float adapted to float on the liquid in the basin and having a mounting independent of the table support and basin, means to move the float mounting and table support vertically relatively at will, and operative connections between said float and said valves, for alternative operation on respective opposite vertical relative movements, a work table, a tool thereover, means to move the table and tool relatively and operative connections between the last named means and said mounting of the float.

7. The structure of claim 1 in which said pointer device consists of a lens over the pattern table, a light beam source over the lens and one being horizontally movable with respect to the other, the operative connection between the means to move the work table and tool relatively being connected with the movable one of the two elements consisting of lens and light beam source.

DARNLEY E. HOWARD.
